(57) **CLAIM**

The ornamental design for a goggle component, as shown and described.

DESCRIPTION

FIG. 1 is a front perspective view of a goggle component showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in the Figures show portions of the goggle component and environmental subject matter (such as, but not limited to, an electronics module) mounted in the goggle component which form no part of the claimed design.
